UNITED STATES PATENT OFFICE.

FREDERIC T. MORSE, OF MARCELINE, MISSOURI.

RAIL-CLIP FOR MEASURING-TAPES.

1,269,840.

Specification of Letters Patent. Patented June 18, 1918.

Application filed December 6, 1916. Serial No. 135,438.

To all whom it may concern:

Be it known that I, FREDERIC T. MORSE, a citizen of the United States, residing at Marceline, in the county of Linn and State 5 of Missouri, have invented new and useful Improvements in Rail-Clips for Measuring-Tapes, of which the following is a full, clear, and exact description.

My invention relates to clips for securing 10 measuring tapes to the ball of railroad tracks, and so forth.

Heretofore civil engineers when making measurements of the beds and ballasting of railroad tracks have, in many of the operations, required one man to hold the end of the tape on the ball of the rail while another measured the distance therefrom of a certain point, and if short measurements had to be made parallel to the tracks, two men were 20 as a rule necessary.

The object of my invention is to enable one man to take both transverse and longitudinal measurements, and particularly in connection with railroad tracks, and enabled 25 to do this accurately and expeditiously unaided by comparatively simple means, substantially as hereinafter fully described, and as particularly pointed out in the claims.

In the drawings:

30 Figure 1 is a plan view of my invention.

Fig. 2 is a side view thereof applied to a rail, which latter is shown in section.

Fig. 3 is a longitudinal section of the same, taken on dotted line 3—3, Fig. 1.

35 Fig. 4 is a perspective view illustrating the manner of its use.

My improved tape-clip consists, preferably, of a continuous stretch of wire which is bent to provide two correspondingly 40 shaped parallel side-frames and cross-bars connecting the ends of the same. These side-frames are provided with straight horizontal bearers *a*, *a*, which when the clip is fastened to the track rail *A* rest upon the tread 45 thereof. At one end of these bearers said frames are bent perpendicularly downward a distance sufficiently below the ball of the rail to form abutting members *b*, *b*, that are adapted to bear against the outer side of the 50 ball of the rail and have their lower ends connected by the cross-bar *c*.

The ends of bearers *a* of the side-frames opposite the abutting members are first bent upward to form loops or eyes *d*, *d*; then perpendicularly downward a distance corresponding to the thickness of the ball of the 55

rail, and then are bent inward and downward toward the vertical web of the rail to form clamping members *e*, *e*. These clamping members are adapted to engage the under side of the inner portion of the ball of the rail and securely clamp the clip to the same, and their lower ends are, preferably, bent downward slightly and connected by a cross-bar *f*.

The bearer portions *a*, *a*, of the clip are connected and spaced apart by a sheet metal plate *B* whose longitudinal edges are rolled upward around said bearers, and at about its center of length this plate is provided 60 with upwardly projecting lugs *C*, *C*, next the inner side of the bearers, and a transverse eccentric boss *D* is suitably journaled in these lugs in such manner that when engaging the tape, as will hereinafter be more 65 fully explained, its major axis is below the rotative axis thereof. This boss has a handle *E* extending from about the center of length thereof toward the vertical plane of the clamping members of the clip by 70 means of which said eccentric boss can be 75 rotatively moved. If desired, however, this handle might extend from said boss in the opposite direction.

Plate *B* is provided with two transverse 85 openings *g* and *h* on either side of boss *D* through which the tape is adapted to be threaded when the clip is being used.

In operation, after the clip has been secured to the ball of the track rail, in the 90 manner hereinbefore explained, the end of the measuring-tape, which it is desired to secure to said rail, is threaded under the end of plate *B* nearest the abutting members, and then up through opening *g* and 95 under eccentric boss *D*, which has been previously moved so as to permit this to be done, and then is threaded down through opening *g* under the end of said plate *B* nearest the clamping members. Handle *E* 100 is then depressed so that the boss will clamp the tape between it and the plate, whereupon said tape can be pulled and drawn taut to any distant point desired, and the distance from said point to the inner side 105 of the rail accurately ascertained.

When the measurements are to be made in the direction of the length of the track, or between points where it would be impossible to use the clip on the ball of the 110 rail, the clip is turned edgewise to the position it occupies when used on the rail, and

2
an ordinary surveyor's pin is thrust down through eyes *d*, *d*, into the ground or other support at the point from which it is desired to measure, and then the tape is drawn 5 to the opposite point of the measurement and the distance between the two points accurately ascertained. The inner diameters of the eyes are, preferably, little less than the diameter of the surveying pins, and 10 thus, when said pins are thrust through them they grasp said pins so tightly that they will not slip on the same. These eyes also provide a certain amount of elasticity to the clamping members and enable the 15 latter to be easily adjusted upon the rail and to clamp the rail.

I do not desire to be confined to the exact construction of the clip and the tape clamping elements used in conjunction 20 therewith as hereinbefore described and as illustrated in the drawings, as it is evident that openings *g* and *h* in plate B, and eyes *d*, *d*, could be dispensed with, and it is also 25 evident that the clip, instead of being constructed of a continuous piece of wire, could be made of other kind of metal members that would answer the same purpose.

What I claim as new is:

1. The combination with a tape measure, 30 of a clip comprising a device to which a measuring-tape can be removably fastened, and means for securing the same to the ball of a track-rail.

2. The combination with a tape measure, 35 of a clip comprising bearers adapted to rest on the tread of a track rail and having the ends thereof bent downward to embrace the sides of the ball of said rail, and a device supported by said bearers by which a tape 40 measure can be removably secured thereto.

3. The combination with a tape measure, 45 of a clip comprising transverse bearers adapted to rest upon the tread of a track rail having one end thereof bent downward and the lower portion of said downwardly 50 bent portion bent toward the web of the rail under the ball of the same, and a device supported by said bearers by which a tape

measure can be removably secured to said 50 bearers.

4. A measuring-tape clip comprising transverse bearers which at one end are provided with integral loops or eyes, and a device supported by said bearers by means of which a tape measure can be removably 55 secured thereto.

5. A measuring-tape clip comprising transverse bearers which at one end are provided with integral loops or eyes, and from thence extend downward to form clamping 60 members and which at the opposite ends thereof are bent downward to form abutting members between which and said clamping members the ball of a track rail is adapted to be clasped, and a device by 65 means of which a tape measure can be removably secured to said bearers.

6. A measuring-tape clip comprising bearers adapted to be removably secured to the ball of a track rail, a flat plate connecting 70 said bearers and an eccentrically journaled boss mounted thereon which is adapted to clamp a measuring-tape between the same and said plate.

7. The combination with a tape measure, 75 of a clip comprising a plate, an eccentrically journaled boss mounted thereon between which and said plate a measuring-tape can be removably secured, and means that support said plate and are adapted to 80 removably secure the same to the ball of a track rail.

8. A measuring-tape clip comprising a plate, an eccentrically journaled boss mounted 85 thereon between which and said plate a measuring-tape can be removably secured, and means for clamping said plate to a suitable support which are provided with eyes at one end.

In witness whereof I have hereunto set 90 my hand this 24th day of November, 1916.

FREDERIC T. MORSE.
